US0D1101338S

(12) **United States Design Patent** (10) Patent No.: **US D1,101,338 S**
Zhou (45) Date of Patent: ** Nov. 4, 2025

(54) REFUSE RECEPTACLE

(71) Applicant: **Zhejiang Erhui Technology Co., Ltd.**,
Taizhou (CN)(72) Inventor: **Ting Zhou**, Zhejiang (CN)(***) Term: **15 Years**(21) Appl. No.: **35/522,954**(22) Filed: **Oct. 16, 2024**

(80) Hague Agreement Data

Int. Filing Date: **Oct. 16, 2024**Int. Reg. No.: **DM/241744**Int. Reg. Date: **Oct. 16, 2024**Int. Reg. Pub. Date: **Nov. 15, 2024**

(30) Foreign Application Priority Data

Aug. 19, 2024 (CN) 202430523590.0

(51) LOC (15) Cl. **09-09**

(52) U.S. Cl.

USPC **D34/7**

(57) CLAIM

The ornamental design for a refuse receptacle as shown and described.

DESCRIPTION

1. Refuse receptacle
- 1.1 : Perspective
- 1.2 : Perspective
- 1.3 : Perspective
- 1.4 : Front
- 1.5 : Back
- 1.6 : Left
- 1.7 : Right
- 1.8 : Top
- 1.9 : Bottom

1 Claim, 9 Drawing Sheets
